OSCAR C. GOERIZ, OF OAKLAND, CALIFORNIA.

ROTARY PUMP.

Application filed October 18, 1922. Serial No. 595,434.

To all whom it may concern:

Be it known that I, OSCAR C. GOERIZ, a citizen of Germany, residing at Oakland, in the county of Alameda, State of California, have invented a new and useful Rotary Pump, of which the following is a specification in such full and clear terms as will enable those skilled in the art to construct and use the same.

10 This invention relates to a rotary pump and its object is to produce a pump which will combine features of the axial flow and centrifugal flow type pumps in the most efficient manner possible to produce a pump capable of having the maximum discharge areas for a given size of pump casing.

It will be understood by those skilled in the art that where pumps are intended to be used in wells of comparatively small diameter, say from 8" to 16", if the pump is a purely centrifugal type, the passageways for the water are of necessity very small, both upon the entrance and discharge sides. These small passageways limit the 25 actual discharge and increase the friction to such an extent as to materially decrease the efficiency of such pumps.

Another object of the invention is to locate the point of fluid discharge of the runner at the hub, so as to give, when connected by a curve with the inlet point at the smaller diameter of the hub substantially the same hydraulic pressure as that obtained at the outer curve of the blade developed along its 30 cylindrical enclosing casing, thus preventing any currents which reduce the pump efficiency.

In furtherance of the object of producing a runner to obtain substantially the same 40 hydraulic pressure across the entire cross section of the moving body of water, and thereby increasing the efficiency of the pump, the curves of the blades along the hub and along the runner periphery are joined by 45 smoothly curved blades gradually changing from one extreme curve to the other extreme curve.

The other objects of the invention will appear as the description proceeds.

50 An embodiment of the invention is shown in the accompanying drawings, in which the same reference numeral is applied to the same portion throughout, but I am aware that there may be modifications thereof.

Figure 1 is a vertical sectional view of a 55 pump made in accordance with the disclosure of this invention.

Figure 2 is a sectional view of a portion of the pump showing the runner lowered to 60 reduce the pump capacity.

Figure 3 is a plan view of one of the runner blades, the dotted lines of the figure indicating radial lines of the pump runner.

Figure 4 is a plan view of the runner, the 65 dot and dash lines indicating the lower edges of the runner blades while the solid lines indicate the upper and outer edges of the blades, the dotted lines indicating the curve along the hub.

Figure 4^a is a bottom plan view of the 70 runner.

Figure 5 is a side elevation of one of the runner blades.

Figure 6 is a view of one of the runner 75 blades looking in the plane of rotation and looking toward its leading edge.

Figure 7 is a view of one of the runner blades looking from the center of the pump toward its periphery.

Figure 8 is a velocity diagram indicating 80 the conditions which must obtain along the flow lines of the impeller blades to combine the effects described.

Fig. 9 is a perspective view of a runner 85 having seven blades drawn from an actual pump runner.

The pump is supported by any suitable fitting 1, which is placed at the top of the ground or upon any suitable frame work. 90 This fitting supports a pipe 2 which extends to a suitable diffuser casing 3, or may be connected to other lengths of pipe in turn connected to the diffuser casing, if the depth of the well requires it.

Supported on the fitting 1 is a suitable 95 frame 4, which carries an annulus 5, within which the thrust bearing 6 is adjustable. This thrust bearing has an inner flange 7 to retain the lubricant for the ball races 8, 9 and balls 10, but, of course, it will be apparent that any form of thrust bearing may be used in place of the one shown.

Resting upon the ball race 8 is a flanged hub 11. This hub is permanently secured 105 to the shaft 12 by a suitable key 13 to support the shaft at any desired elevation, for the purpose of regulating the output of the pump without changing the speed of the

runner. The bearing support has laterally projecting lugs 14 and 15 through which adjusting screws 16 and 17 pass. These screws bear upon the frame work 4, and are 5 located in any given adjustment by nuts 18 and 19.

The diffuser casing 3 is secured to the lower end of the pipe 2 or extra lengths of pipes, if more than one length is used, in 10 any suitable manner, screw threads being shown in the present instance, and it has a plurality of curved diffuser blades 21, said blades being of any acceptable form to reduce the flow of water to the desired velocity. 15 The cross sectional area of discharge of these blades is greater than their cross sectional area of inlet at the bottom. They are connected to the outer portion of the shell 3, and are connected at their inner edges to the 20 frustum of a cone 22. The outer portion of the shell 3 is swelled out at 23 to give the necessary outward flow lines to the water as it is discharged from the runner below.

The diffuser hub has bearings 24, 25 for 25 the proper support of the shaft 12.

The pump runner comprises a conical hub 26 which is connected to the shaft by means of a suitable key 27 and nut 28, and it has a 30 plurality of blades 29 extending peripherally therefrom. These blades are developed to give equal lifts over all of the impeller surfaces along the various flow lines, assuming the efficiency to be constant. This construction will be given in accordance with the 35 following mathematical formula.

Assuming the peripheral velocity V' at the entrance and V'' at the discharge edge, the tangential projection of the absolute velocities U' and U'' at both points, then 40 all over the flow lines the condition V'' multiplied by U'' minus V' multiplied by U' equals a constant; this will give substantially equal lifts all over the impeller blade surfaces.

45 Following out this formula develops a blade which gives substantially axial flow C' at its entrance edge and a combined axial and tangential flow C'' at its uppermost discharge edge with variations thereof at all intermediate points, the blade varying both in axial and radial pitch.

In order for the water to be directed to the pump runner without eddying, there is 50 a bottom ring 31 secured on the bottom of the casing 3, and it has vertical blades 32 to prevent eddying the water led to the runner blades 29. The pump runner blades 29 have their leading edges A extending from 55 a point below the conical hub 26 upwardly and backwardly to connect with the hub in a plane indicated by the dotted line Figure 9 just about one quarter the height of said hub. The outer edges of the blades are indicated at B and they extend substantially concentric with the runner axis to a point about

one third their height below their tops at which place they turn sharply in toward the top of the hub as shown at C. (Note upper dotted line Figure 9.) The runners are, of course, cast with and connected to the hub forming a smooth curve D receding from the leading edges and then extending upwardly and outwardly to the top of the blades as shown in Figure 9. Now by observing the lower edges of the runner blades (Fig. 1 at the left) it will be seen that the only thing that portion of the blade up to the section line of the blade, can do (that point representing the narrowest portion of the opening between blades and casing) is to move the water axially. At that point the casing widens and the blade shape changes so the water can now pass laterally and upwardly into spaces between the diffuser blades 21. The water is discharged from the pump through the launder L.

With the present invention, an object is to produce a high capacity runner for large volumes and high pressures, this high capacity being attained by the use of large 90 entrance areas into which the water flows, principally axially, and by having the maximum diameter for the discharge substantially as large as the maximum inlet diameter of the runner, while the smallest diameter for the discharge is selected sufficiently 95 far above and inwardly from the stated point of the discharge, at the maximum diameter, to prevent choking of the water, and to allow it to move along easy flow zones, as indicated at the dotted lines, Figure 1.

It thus follows from the above that the smallest discharge diameter is smaller than the maximum diameter at the inlet side of the runner for the standard capacity runner. Reductions in capacity of this standard runner are preferably made by lowering the runner from its normal position whereby the discharge area is reduced within the 100 allowable limits of adjustment of the pump. The two effects are merged into one another by connecting the necessary extreme inner and outer curves by blades having gradual 105 changes of direction from one form of curve to the other. This results in the production of a runner which has its blades to give axial flow to the water at its periphery, while the blades at their inner portions, are so shaped as to give the necessary centrifugal flow to the water so that the pressure of the water traveling upwardly and outwardly along the inner portions of the blades will be substantially the same as the pressure of the water traveling upwardly along the outer 110 periphery of the pump runner, thereby operating with the highest efficiency, intermediate portions of the blades being merged from one form to the other with the gradual 115 changes of direction, previously mentioned.

120 In the pump shown only one stage is indicated.

cated, but this pump is especially adapted to multiple stage operation since two, three or more of the shells 23 and associated parts may be coupled together when greater pressures are required than one stage can supply. Only one bottom section 31 is used no matter how many stages are used.

What I claim is as follows, but various modifications may be made in the construction shown in the drawings and above particularly described form, within the purview of my invention.

1. In a turbine pump, a series of diffuser blades, a runner adjacent the same, said runner having a frusto conical hub and blades connected therewith, which blades have their surfaces adjacent the line of contact with said hub and their surfaces at their peripheries developed along different spirals, the blades having their intermediate surfaces merged from one curve into the other with gradual changes of direction, and a casing within which said runner rotates.

2. In a turbine pump, a casing, a series of diffuser blades therein, a runner adjacent the diffuser blades, said runner having a frusto conical hub with blades connected therewith, which blades have their surfaces adjacent the hub and adjacent their peripheries developed along different spirals, the intermediate surfaces of each blade merging from one curve into the other with gradual changes of direction, and a cylindrical casing within which the runner rotates.

3. In a turbine pump, a casing, a series of diffuser blades, a runner adjacent the diffuser blades, said runner having a frusto conical hub with blades connected therewith, which blades have their surfaces adjacent the hub and the surfaces at the periphery of the blades developed along different spirals, the intermediate surface of the blades merging from one curve to the other with gradual changes of direction, and a cylindrical casing surrounding the blades, the casing being enlarged above the blades.

4. In a turbine pump, a series of diffuser blades, a runner adjacent the same, said runner having blades developed along a hub approaching a cone at their inner edges and along a flat spiral to give a substantially axial and circular line of movement to the

fluid at their peripheries, and a cylindrical casing surrounding said blades.

5. A high pressure turbine pump impeller having blades peripheries of which are cylindrical, and a casing surrounding the same having a cylindrical bore within which the impeller rotates, diffuser blades carried by said casing, and means to vary the position of the impeller blades with respect to the diffuser blades whereby the discharge from the pump may be varied without varying the speed of rotation of the impeller.

6. A high pressure turbine pump comprising a driving shaft, a conical hub carried thereby, spiral blades carried by said hub the outer edges of which blades are located in a cylinder, and a casing surrounding the impeller and within which it rotates, said casing being of greater interior diameter above the impeller than at the cylindrical portions of the impeller blades.

7. A high pressure turbine pump comprising a shaft, a conical hub carried thereby, smaller at the inlet side, spiral blades carried by said hub, said blades projecting beyond the plane of the narrowest portion of said hub and tapering out to the periphery of the hub at its widest part, whereby substantially the same pressure over the entire surface of the impeller blades between the conical hub and the outer periphery thereof will be produced, and a cylindrical casing within which said impeller rotates.

8. A high pressure axial flowing turbine pump for deep wells comprising a shaft, a conical hub carried thereby smaller at the inlet portion, spiral blades connected with said hub, the outer edges of which terminate in a cylinder, and the lower ends of which are pointed and project below the narrowest portion of said hub, the upper ends of said blades tapering out into the widest part of the hub, whereby substantially the same pressure over the entire surface of the impeller blades between the conical hub and their periphery will be produced, and a cylindrical casing within which said impeller rotates.

In testimony whereof I have hereunto set my hand this 10th day of July, A. D. 1922.

OSCAR C. GOERIZ.
